UNITED STATES PATENT OFFICE.

WALTHER BAUERSFELD AND FRANKLIN PFEIFFER, OF JENA, GERMANY, ASSIGNORS
TO THE FIRM CARL ZEISS, OF JENA, GERMANY.

PHOTOGRAPHIC SHUTTER.

Application filed March 30, 1928, Serial No. 266,072, and in Germany February 8, 1926.

The present invention relates to photographic shutters, which are to be disposed at the locus of the camera objective and which contain a plurality of rotatable shutter 5 blades, partly overlapping each other. The invention consists in this that with these shutters the blades are constructed as spherical bowls, and not, as heretofore, as plane discs. Thereby one attains in the first 10 place a great rigidity of the blades, so as to be able to render them particularly thin; moreover, a very compact structure of the shutter is thereby attained.

The annexed drawing shows as an example 15 a shutter according to the invention.

Fig. 1 represents a section through the shutter along the objective axis, Fig. 2 a perspective view of the shutter with the casing removed, looking in the direction of the 20 arrow shown in Fig. 1, Fig. 3 a front view of one of the shutter blades and Fig. 4 a section on the line 4-4 of Fig. 1.

The shutter shown contains four blades *a*, recessed according to Fig. 3 and constructed 25 as spherical bowls, which are rotatably supported on a spherical casing *b* with axes *c*. On the latter are fixed driving wheels *d*, engaging in a gear *e* of a bevel wheel *e* rotatable about the casing *b*. The bevel wheel has also 30 a second gear *e*, coacting with a curved wheel *f*, which is rotatably supported on the casing *b* by means of an axis *g*. On the wheel *f* there are fixed two ratchet wheels *f*¹ and *f*². By means of two ratchets *h*¹ and *h*², engaging 35 in these wheels, the latter and also the wheel *f* are coupled to a spring casing *i* on which the ratchets are fixed rotatable about an axis *h*³. The spring casing is likewise rotatable about the axis *g* and within the same 40 there is supported a spiral spring *i*¹. The one end of this spring is fastened in the spring casing *i*, whilst the other is rigidly connected to a worm wheel *i*², rotatable about the axis *g*. The worm wheel meshes with a 45 worm *i*³, which is supported on a standard *j* fixed on the base *b*¹ of the casing and provided with a milled head *i*⁴. The spring casing carries in addition a handle *i*⁵, two noses *i*⁶ and *i*⁷ and a stop *i*⁸, which during clockwise 50 rotations of the spring casing strikes against a plate *j*¹, fixed on the standard *j*. Between the worm wheel *i*² and the spring casing *i* there is disposed a spur wheel *k*, which is rigidly connected to the worm wheel

*i*² and engages in a wheel *k*¹. The latter is 55 supported on a standard *k*² fixed on the base plate *b*¹ and engages in a toothed sector *l*, which is rotatable about a bolt *l*¹ fixed on the spherical part of the casing *b*. On the bolt is fixed a spring casing *l*² in which is 60 disposed a spiral spring *l*³, the one end of which is fixed on the nave of the toothed sector *l*. The other end of the spring is free and extends below the nose *i*⁷ of the spring casing *i*. To the casing *b* of the shutter there is also 65 rigidly connected a pin *m* which serves for releasing the ratchet *h*¹. Besides there is provided a spherical body *n*, which is destined to receive a part of the photographic objective, whilst the other part of the objective is to be fixed on the casing itself. In addition, there is provided a disengaging friction brake for the wheel *f* whose friction disc is formed by the wheel *f*¹. As a brake shoe 70 serves the head *o* of a rod *o*¹, which is guided in a sleeve *o*², fixed on the base plate *b*¹, and which rod is under the action of a spring *o*³. The sleeve *o*² has a slot *o*⁴ through which passes a pin *o*⁵, fixed on the rod *o*¹. The pin *o*⁵ extends behind a pawl *p*¹ to be released by 75 hand and being under the action of a spring *p*, which is supported on the base plate *b*¹ at a standard *p*². All actuating parts of the shutter are covered by a lid *b*².

The operation of the shutter takes place 85 in the following way. The shutter is to be wound up by rotating clockwise the spring casing *i*. Thereby the latter is rotated by means of the handle *i*⁵ until the stop *i*⁸ strikes against the plate *j*¹ in which case the pawl *p*¹ acts behind the nose *i*⁷, so as to prevent the spring casing from turning back. On rotating the spring casing the ratchet *h*¹ slips along the pin *m*, viz, in the first place with a part concentric with the axis of rotation *g* of the spring casing, so that the position of the ratchet *h*¹ does not undergo a change. Consequently, the ratchet remains in mesh 90 with the ratchet wheel *f*¹, and the latter with the wheel *f* as well as the bevel wheel *e*, the driving wheels *d* and the blades *a* are turned backwards together with the spring casing. The arrangement is such that the blades *a* are thus rotated in a backward direction 95 through 60°. After the rotation of the spring casing *i*, corresponding to the aforesaid angle, the ratchet *h*¹ comes to lie under the pin *m* with a part projecting beyond that part 100 105

of it which is concentric with its axis of rotation g . Thereby the ratchet releases the wheel f^1 and the latter, as well as the blades a , remain in the position attained, while the 5 spring i^1 is still further wound up. The release of the shutter is effected by a pressure upon the roughened part of the pawl p^1 . Thereby the pin o^5 is at first moved in a backward direction, so that the brake shoe o releases the wheel f^1 . At the same time there is 10 released the nose i^6 and the spring casing i jerks back into its original position. Thereby the ratchet h^2 rotates the ratchet wheel f^2 and the blades a ; these latter are rotated 15 through 420° , so that they resume that position which they held prior to the winding-up of the shutter. During the rotation of the blades a through 420° all recesses of the blades come to lie simultaneously in front of the 20 lenses of the objective, whereby the shutter is at full aperture. However, the opening does not begin simultaneously with the jerking back of the spring casing but only after the latter and all parts to be moved have been 25 moved somewhat. Thereby it is attained that during the proper opening-period the blades a move at a uniform speed and need not first be accelerated during this period. At the 30 end of the opening period the nose i^7 strikes against the free end of the spiral spring b^3 by which a shock at the end of the motion of the blades is prevented. In order that sufficient ranges for the initial acceleration, for the opening-period and for the gradual 35 standstill of the masses are available, one has chosen the comparatively large angle of rotation of the blades of 420° , which necessitates a backward movement of the blades by

the amount surpassing 360° at the beginning of the winding-up of the shutter. 40

The variation of the elasticity of the actuating spring i^1 and of the duration of the opening-period is effected by rotating the milled head i^4 . Thereby one also attains a variation of the elasticity of the spring b^3 , so 45 that to the amount of the force actuating the blades a , there always corresponds the amount of the force lessening the motion of the blades at the finish. 50

We claim:

1. Photographic shutter, comprising a plurality of shutter blades rotatably disposed, these blades having the shape of spherical bowls, a spring for actuating the shutter blades, means for winding up this spring, 55 coupling means adapted to impart to the shutter blades, on the said spring being wound up, a rotation through over 360° , and means for releasing the spring. 60

2. Photographic shutter, comprising a plurality of shutter blades rotatably disposed, these blades having the shape of spherical bowls, a spring for actuating the shutter blades, and a second spring for checking the motion of the shutter blades. 65

3. Photographic shutter, comprising a plurality of shutter blades rotatably disposed, these blades having the shape of spherical bowls, a spring for actuating the shutter blades, a second spring for checking the motion of the shutter blades, and means for simultaneously varying the elasticity of both 70 springs in the same sense. 75
